Primary Examiner — Mitchell Siegel(57) CLAIM

The ornamental design for a golf club head, as shown and described.

DESCRIPTION

FIG. 1 is a top perspective view of a golf club head;
 FIG. 2 is a bottom perspective view of the golf club head of FIG. 1;
 FIG. 3 is a front view of the golf club head of FIG. 1;
 FIG. 4 is a rear view of the golf club head of FIG. 1;
 FIG. 5 is a top view of the golf club head of FIG. 1;
 FIG. 6 is a bottom view of the golf club head of FIG. 1;
 FIG. 7 is a left view of the golf club head of FIG. 1; and,
 FIG. 8 is a right view of the golf club head of FIG. 1.
 The broken lines shown in one or more of the figures are for illustrative purposes only and form no part of the claimed design.
